LOG TURNER

John A. Weber, Portland, Oreg., assignor to
John T. Anderson, Portland, Oreg.

Application September 15, 1944, Serial No. 554,253

6 Claims. (Cl. 143—97)

1

This invention relates to log turners and is particularly adapted to standard saw mill carriages and log decks.

The primary object of my invention is to provide a log turner device that will speed up the log turning operation.

Another object of my invention is to provide a log turning device that will not destroy or mar the lumber.

A still further object of my invention is to prevent damage to the carriage in the turning of large logs.

A further object of my invention is to design a log turning device that can be readily adapted to any standard saw mill carriage.

These and other incidental objects will be apparent in the drawings, specification and claims.

Referring to the drawings:

Figure 1 is a plan view of my new and improved log turning device mounted upon a saw mill carriage of conventional design.

Figure 2 is a sectional end view, taken on line 2—2 of Figure 1, looking in the direction indicated, illustrating the mechanism for moving the log toward the knees of the head rig.

Figure 3 is the same view as Figure 2, but illustrating the log being moved towards the knees of the head rig.

Figure 4 is a sectional view, taken on line 4—4 of Figure 1, illustrating the raising means for operating the mechanism illustrated in Figures 2 and 3.

Figure 5 is an end sectional view, illustrating the log turning arm and its associated operating elements, the same being taken on line 5—5 of Figure 1, looking in the direction indicated.

Figure 6 is a fragmentary end sectional view of the carriage and log skid having specially designed log stop and glider mounted thereon.

Figure 7 is a fragmentary detailed sectional view of the log turning arm and its associated driving elements.

Figure 8 is a fragmentary plan view of the log turning arm, partially in section, illustrating the operating mechanism connected thereto for raising the arm and turning the log.

Figure 9 is a plan view of the log skid illustrating my new and improved log stops and glider mechanism.

Figure 10 is a fragmentary sectional view of the log transfer chain arrangement, taken on line 10—10 of Figure 3, looking in the direction indicated.

Figure 11 is a sectional end view of a one revo-

2

lution clutch used in the operation of my new and improved log turner.

Figure 12 is a sectional side view of the clutch, taken on line 12—12 of Figure 1.

Figure 13 is a fragmentary plan view of the clutch operating mechanism, taken on line 13—13 of Figure 12.

In the drawings:

A conventional saw mill carriage is indicated by numeral 1, mounted upon the usual supporting wheels 2 and running on tracks 3 and 4. I will first describe the construction and operation of the log turner, which consists of one or more arms 5, each pivotally mounted upon a shaft 6 journaled within suitable bearings 7 mounted and secured to the frame 8 of the carriage.

The shaft 6 is fixedly mounted within the arm 5 by the key 6A (Fig. 7) and revolves within the bearings 7. Fixedly mounted to the shaft 6 is a spur gear 9, this gear is driven by the gear 10, which is keyed to the stub shaft 11 running within the bearing 12. There are a limited number of teeth 13 formed upon the gear 10 for driving the gear 9 only a partial revolution, while the gear 10 makes a complete revolution. The gear 9 raises the arm 5 to a predetermined angle relative to the head block, therefore, when the gear 10 has travelled the distance covered by the teeth 13 these teeth will disengage from the gear 9 allowing the arm 5 to return to its lowered position against the stop 5'. See Fig. 5.

The shaft 11 has a sprocket 14 fixedly mounted thereto and driven by the chain 15 from the countershaft 16, which is journaled to suitable bearings 17 upon the frame of the carriage. The countershaft 16 has sprockets 18 keyed thereto and driven from the clutch assemblies 29 and 20' through the chains 21 and 22. The clutches 20 and 20' provide two different speeds for driving the counter shaft 16.

A driving shaft 25 is driven by a motor 50 and speed reducer 51, and is journaled within bearings 26 on the carriage. A drum 27 is fixedly secured to the shaft 25 by the key 28 (Fig. 12) and revolves therewith. Rotatably mounted on the shaft 25 are the clutch units 20 and 20', consisting of a hub 31, driving arm 30 and a housing 32, having a locking mechanism mounted therein. This locking mechanism consists of a sliding bolt 33 and works within the grooves 34 of the housing 32. The bolt 33 is forced toward the drum 27 by the spring 35. The spring 35 has its outer end resting against a suitable stop 35' and its opposite end against the bracket arm 37 of the bolt 33. The bolt 33 is held out of engagement with the

stops 29, forming part of the drum 27, by the holding bar 38.

The holding bar 38 is pivotally mounted to the frame of the carriage at 79 on its one end, having its opposite end 44 resting upon the clutch assemblies. See Fig. 4. Adjustably mounted upon the holding bar 38 is a cam assembly 38' (Figs. 11 to 13), having a cam surface 40 extending downwardly therefrom in a vertical plane. This cam is for the purpose of disengaging the bolt 33 from the stops 29 within the drum 27. An upwardly extending boss 39 forms part of the bolt 33.

In the operation of the clutch, the side 45 of the boss 39 engages the side 46 of the cam assembly 38', holding the bolt 33 out of engagement with the stops 29. Guides 32', forming part of the clutch assembly extend upwardly and engage the side of the cam assembly to relieve the latter from the tension of the spring 35, while the clutch is being held out of engagement.

Referring to Figure 4, when it is desired to operate the clutch, which is a one revolution type of clutch, the pedal 42 is lowered pivoting the arm 43 about its center and raising the end 44 of the holding bar 38 and its cam assembly out of engagement with the upwardly extending boss 39, allowing the spring 35 to force the locking bar 33 into engagement with the stops 29 of the drum 27, which will rotate the clutch assembly with the shaft 25, driving either of the chains 21 or 22 by sprockets 23 and 24, whichever was selected, and rotating the countershaft 16 and operating the log turner arm 5, as heretofore described. The sprockets 23 and 24 are respectively keyed to the hubs 31 of the clutch assembly.

The pedal 42 is operated momentarily and immediately released, allowing the holding bar 38 to lower to its normal position where the cam 40 will be in line with the upwardly extending boss 39 when one revolution has been completed by the clutch assembly. The sloping surface 47 of the upwardly extending boss 39 engages the sloping surface 40 of the cam assembly 38', camming the locking bolt 33 out of engagement with the stops 29, after which the surface 46 of the cam assembly 38' will hold the boss 39 in retracted position, as shown in Figure 13. The boss, on further travel, will contact the surface 48 of the stop 49, holding the clutch assembly from further rotation.

The object of having the double clutch assemblies 20 and 20' is to provide two speeds for the countershaft 16, as the sprocket 23 of the clutch assembly 20 is larger than the sprocket 24 of the clutch assembly 20', it can be readily understood that these different speeds may be had through the selection of either of the clutch assemblies. The reason for the different speeds to the countershaft 16 is to impart a faster or slower turn to the log through the arm 5 and this speed will be determined by the turning speed of different types of logs.

I will now describe the operation of the transfer chain assemblies 52 and 53, which are mounted transverse the carriage 1. Each of these assemblies consist of side frames 54 and 54', which are fixedly secured to the carriage by suitable fastening means. An arm 55 is pivotally mounted between these frames at 56 and has cams 100 extending downwardly therefrom for resting on the eccentric 57, which is fixedly secured to the countershaft 58 by any suitable means. See Figs. 2 and 3. A chain 54A, preferably of the roller

type, is trained about the upper surface or ridges 55' of the arm 55, curving about the end 55'. The chain is driven by the sprocket 25', which is keyed to the driving shaft 25 and is driven constantly therewith. The lower run of the chain 54A travels over the idler wheel 57' which is rotatably mounted to the countershaft 58.

In the operation of my transfer chain, referring to Figures 2 and 3, when it is desired to move the log 63 towards the head rig 101, after it has been turned, the countershaft 58 is revolved one-half revolution bringing the eccentric 57 to the position shown in Figure 3. This is accomplished by operating the clutch assembly 20'', which, preferably, is substantially identical to the clutch assemblies 20 and 20'. The clutch 20'' will turn one revolution, driving the countershaft 58 one-half of a revolution through the sprocket 105, chain 106 and the driving sprocket 108, (Fig. 4) the driving sprocket 108 being one-half of the diameter of the sprocket 105, thereby rotating the countershaft 58 to the position shown in Figure 3. As the chain 54A operates continuously there will be a movement towards the head rig by the log 63 until the arm 55 is lowered by again operating the clutch assembly 20'', rotating the countershaft 58 to the position shown in Figure 2, thereby lowering the transfer chain assembly to inoperative position.

I will now describe the operation of my deck rolls. Referring to Figures 6 and 9, I replace the ordinary deck rolls with what I term gliders, indicated by numeral 88. These gliders are pivotally mounted to cross shafts 84, which are journaled within brackets or frames 91, which in turn are mounted upon the framework 61' of the log deck 61. Eccentrics 83 are fixedly mounted to the cross shaft 84. The cross shaft 84 is driven by the clutch assembly 85, which is mounted on the countershaft 75. The clutch assembly and its drive sprocket 86 drive the shaft 84 through the chain 87 and driven sprocket 88 when the clutch is engaged.

Referring to Figure 6, the glider is shown in raised position having the log 63 resting thereon after being turned by the turner arm 5. When the turner arm 5 drops back into inactive position the log will glide over the surfaces 82 and the rollers 82' of the glider bars 86 towards the head rig and over the transfer chain assemblies 52 and 53, which will then be raised as heretofore described, transferring the log towards and against the knees 101 of the carriage. The log will then be shifted into sawing position by the usual method of moving the knees 101 or head rig towards the saw. The construction of the clutch assembly 85 is the same as that of the clutches 20 and 20', a one revolution type clutch, having the holding bar 89 operated through the cable system 90 from the operator's station.

When the holding bar is momentarily operated by means of the cable 90, the eccentric 83 is raised to the position shown in Figure 6, the clutch 85 making one revolution and pivoting the eccentric to the position shown, whereupon the holding bar 89 operates to disengage the clutch, as heretofore described with respect to the clutches 20 and 20'.

When it is desired to lower the glider bars 86, the cable 90 is again operated, causing the clutch assembly 85 to pivot the eccentric 83 to its lower position, allowing the glider bars 86 to pivot to their inactive positions, as shown by the dotted lines 86'. The log 63 resting on the log deck skid

61 is held in position to be supplied to the head rig by the pivotally mounted stop 64, as shown in Figure 6. The stop 64 is normally in the position shown in Figure 6, but when it is desired to allow the log to enter its position over the glider bars, the clutch assembly 76 is operated by its holding bar 77 and cable 78, rotating the eccentric 70 one revolution within the eccentric ring 69, which in turn transfers this motion through the connecting rod 68 to the pivot 67 of the holding bar 64, thereby rocking the bar about its center shaft 65, releasing the log 63, allowing it to roll down the skid 61. The holding bar 64 is half moon in shape and the pivot point 67, when raised by the eccentric 70, will give the log 63 an initial boost if necessary, causing it to roll down the skids.

A shock absorber arrangement is provided for the connecting rod 68, through the action of the movable connecting yoke 66, which is slidably mounted within the guide way 66' of the connecting rod 68 and working against the spring 68' forming part of the connecting rod assembly. This shock absorber absorbs the shock of the log when rolling down the skid and against the top 64. Suitable means is provided for preventing any movement of the stop 64 until operated by the clutch assembly. This holding mechanism may consist of a ratchet wheel 71, fixedly mounted to the countershaft 70' and held from back rotation by the pawl 72. The countershaft 70' is mounted within suitable bearings attached to the skid way and is driven through a chain 73 from the driving sprocket 74 associated with the one revolution clutch assembly 76. The clutch assemblies 76 and 85 are mounted to the countershaft 75, which in turn is driven by the motor 92, speed reducer 93, chain 94 and driven sprocket 95, see Figure 9.

In the operation of my new and improved log turner the log 63 is released by the locking bar 64 by the operation of the clutch assembly 76, through the control cable 78. This will cause this assembly to rotate the eccentric 70 one revolution, lowering the stop 64 and releasing the log and raising the stop again to catch the next log to come. The log 63 then rolls into position over the glider bars 80, transfer chain assemblies 52 and 53, which form part of the carriage as heretofore described. The log will come to rest against the knees 101 on the carriage, which will position the same to sawing position.

After the proper number of cants are removed from the log the log will then be turned by the turning arm 5, which is operated by either the clutch assembly 28 or 20' as heretofore described. At the same time the glider bars 80 will be raised to the position shown in Figure 6, as heretofore described, through the clutch assembly 85, the log will strike the glider bars 80, as illustrated in Figure 6, and when the turning arm 5 is lowered the log will glide back on to the carriage over the surface 82 and roller 82' at which time the transfer chains 54A will be raised to the position shown in Figure 3, as heretofore described, which will move the log 63 back against the knees 101 of the head rig, at which time the transfer chains will be lowered to the position shown in Figure 2 and the head rig 1 will move the log forward to the cutting position shown.

It will be noted in all of these operations that the log is handled by lifting or moving without hooks or the like marring the timber. This is one of the primary objects of my invention, preservation of the lumber which can be accomplished

through the use of my invention having no hooks of any sort grabbing into the log.

I do not wish to be limited to the exact structure or mechanical parts, as other mechanical equivalents may be substituted, still coming within the scope of my claims.

I claim:

1. A log handling mechanism comprising a log deck, a carriage movable to a position adjacent said log deck, a shaft journalled on said carriage, a log turning arm rigidly mounted on said shaft and normally held by gravity in a horizontal inoperative position, a spur gear keyed on said shaft, a stub shaft journalled on said carriage, a mutilated gear mounted on said stub shaft and engageable with said spur gear to move said turning arm, said gears being engageable for a partial revolution of the spur gear while the mutilated gear makes a complete revolution to swing the turning arm upward to a predetermined position for turning the log and then said spur gear and turning arm moving back to a normal position to release the log, means for driving said mutilated gear to operate said arm, glider bars movably mounted on said deck to receive the log as it is turned by said arm, and means for moving the glider bars to positions inclined toward said carriage to move the turned log toward and onto said carriage after the turning arm has returned to normal position.

2. A construction as defined in claim 1 wherein the glider bars are pivotally mounted with respect to the deck and are normally below the plane of the deck, and wherein the means for raising said glider bars above the plane of the deck to position the operative surfaces of said glider bars at an incline toward the carriage operate during operation of the turning arm.

3. A construction as defined in claim 1 wherein said means for driving said mutilated gear includes a driving shaft having independent chain and sprocket connections with said mutilated gear, the sprockets on the driving shaft varying in diameter to impart variable speeds to said mutilated gear, and manually operable clutches for selecting the particular sprocket to be driven by the driving shaft to selectively control the speed of operation of the turning arm.

4. A construction as defined in claim 1 wherein the means for driving said mutilated gear includes clutches each comprising a driven drum having peripheral and independent stops, a clutch unit on each side of the drum, a sliding bolt in each unit to cooperate with the independent stops of the drum, means for automatically operating each bolt into clutch cooperation with a selected stop in the drum and a manually operable element to automatically withdraw the bolt from clutching operation with the said stop of the drum following one revolution of the drum.

5. A construction as defined in claim 1 wherein the means for driving said mutilated gear includes clutches each comprising a driven drum having peripheral and independent stops, a clutch unit on each side of the drum, a sliding bolt in each unit to cooperate with the independent stops of the drum, means for automatically operating each bolt into clutch cooperation with a selected stop in the drum and a manually operable element to automatically withdraw the bolt from clutching operation with the said stop of the drum following one revolution of the drum, and means on the element to normally hold the bolt against clutching cooperation with the stops of the drum.

6. A construction as defined in claim 1 wherein

the glider arms are each provided in its log engaging surface with a roller projecting beyond such log engaging surface to elevate the end of the log moving toward the carriage.

JOHN A. WEBER.
